(57) **CLAIM**

We claim the ornamental design for a hip-carried vacuum cleaner, as shown and described.

DESCRIPTION

FIG. 1 is a front perspective view of a hip-carried vacuum cleaner showing our new design;

FIG. 2 is a front elevational view thereof, attached to a hip-mounting harness shown in broken lines;

FIG. 3 is a rear view thereof;

FIG. 4 is a side view thereof;

FIG. 5 is a side view showing the side opposite that shown in FIG. 4;

FIG. 6 is a top plan view thereof; and,

FIG. 7 is a bottom plan view thereof.

The broken lines in the Figures is for the purpose of illustrating exemplary environmental structure and forms no part of the claimed design.
